JOSEF SCHLOTMANN, OF OBERHAUSEN-RHEINLAND, GERMANY, ASSIGNOR TO FIRM: GUTEHOFFNUNGSHÜTTE OBERHAUSEN AKTIENGESELLSCHAFT, OF OBERHAUSEN-RHEINLAND, GERMANY

MEANS FOR UNIFORMLY COOLING HOT BLAST AND HOT GAS GATE VALVE DISKS

Application filed December 24, 1931, Serial No. 582,972, and in Germany December 27, 1930.

Water-cooled hot-blast gate valve disks are known to have their cooling chamber subdivided by different cross walls for guiding the cooling water, these cross walls producing however unequal cross sections when applied to a round disk, preventing thereby a uniform cooling effect and a sufficient flow of water to all parts. In particular the formation of air and steam pockets was rendered possible thereby, which prevent the heat from being eliminated and which moreover promote the formation at the surfaces not touched by the flow of water of deposits of mud contained in the cooling water with the effect that within the range of these places the walls of gate valve disks are exposed to a rapid destruction owing to the destructive action of heat. The object of the invention is to provide an improvement for gate valve disks which avoids the drawbacks described heretofore and which makes them last for a considerably longer time. The cooling water chamber is subdivided by cross walls into channels of preferably spiral shape having an approximately equal cross section through which channels the cooling water is guided changing several times its direction. Deposits of mud and air pockets are avoided to a considerable extent by the cross walls being provided within the range of the points where the flow of water is reversed, as well as at the highest points with vents through which the gases or vapours carried along by or generated in the water are eliminated. Thereby the flow of water always will keep its closed nature and will proceed in a uniform current thus preventing in a high degree the formation of mud deposits and of places where cooling is less efficient.

With reference to the accompanying drawing:

Fig. 1 shows a vertical section through a gate valve disk in a gate valve generally outlined in its open position, and

Fig. 2 shows a cross section on line A—B of Fig. 1, when the valve is closed.

In the interior of the valve body V in a manner well known in itself the gate valve disk *a* is movably arranged and is kept adjustable as to its position by a rope connection with counterweight, by a threaded spindle or by some other suitable means. According to the invention the cooling chamber of the gate valve disk is subdivided by cross

walls *b* into cooling channels curved to a convenient spiral shape which for instance enable the cooling water to flow through the subsequent channels in alternating direction. Moreover the channels will have preferably almost equal cross sections so as to keep the speed of flow of the cooling water approximately constant at all points. At the points where the cooling water changes its direction, as well as at the highest points of the cooling chambers vents *c* are provided in the guide walls *b* through which vents all gases and vapours carried along by or generated in the water are eliminated and leave the gate valve disk together with the flowing-off cooling water. *d* designates the inlet pipe and *e* the discharge pipe for the cooling water. The uniformity of the cooling effect can be increased by intermittent change in the flow of the cooling water so as to cause the discharge pipe *e* used hitherto for this purpose to serve as inlet pipe, while the previous inlet pipe *d* discharges the cooling water.

The covering plate *a'* conveniently is secured to the gate valve disk *a* at the points *f* by screws or other means of fixation and at *f'* by means of welding. It is to be understood, of course, that the disk may be manufactured in any other way.

Besides for hot blast and hot gas gate valve disks, the invention is also to be understood as applying to all other water-cooled closing means of the sliding or turning type exposed to high temperatures.

What I claim is:

1. A hot blast valve, or the like, comprising in combination with a valve casing, a hollow valve member of substantially circular cross-section provided with spaced curved partitions forming substantially spiral-shaped channels, said partitions having vent-holes therein at certain intervals.

2. A hot blast valve, or the like, comprising in combination with a valve casing, a hollow valve member of substantially circular cross-section provided with uniformly spaced curved partitions forming substantially spiral-shaped channels, said partitions having vent-holes at certain intervals, and a cover secured to said hollow valve member.

JOSEF SCHLOTMANN.
